(57) **CLAIM**

The ornamental design for an anti-bacterial fogger, as shown and described.

DESCRIPTION

FIG. 1: is a top right perspective view;

FIG. 2: is a top plan view;

FIG. 3: is a bottom plan view;

FIG. 4: is a front elevation; and,

FIG. 5: is a right side elevation.

The surfaces opposite to the view shown in FIG. 1 continue the configuration and surface appearance of the portions shown.
